UNITED STATES PATENT OFFICE

JOSEPH W. HENNECKE, OF LOS ANGELES, CALIFORNIA

LATHING HAMMER

Application filed November 13, 1929. Serial No. 406,804.

This invention relates to improvements in lathing hammers and similar tools. In order to fully appreciate the nature and advantages of the improved lathing hammer, a brief résumé of the desiderata involved in the construction of such a tool is believed to be necessary.

Lathers are generally employed on a piece work basis so that it is highly essential that the lather be capable of working as speedily and as efficiently as possible at all times. In such work, where very little manual labor is wasted, it is highly essential that the lathing hammer or lathing axe be perfectly balanced and suitable to the user. It is also customary for lathers to keep the edge of the blade on their lathing hammers as sharp as possible; also to keep the hammering face with a fairly sharp knurled or roughed surface. In the course of time as the blade becomes dull and is sharpened and re-sharpened, the length and weight of the blade decrease, throwing the hammer out of the customary balance. Likewise if the knurled or roughened surface on the hammer head wears and becomes smooth, the lathing nails cannot be driven as easily or as efficiently with the hammer.

Heretofore, with one exception, it has been customary to construct a tool of this character with an integral or single piece head, which forms both the hammering face and the blade. As the hammering face and blade become worn, throwing the tool out of perfect balance, the ultimate limit is eventually reached wherein the lather discards his old tool entirely and replaces it with an entirely new tool. This the usual lather dislikes to do because frequently he has become thoroughly accustomed to the grip or the handle of the tool and in discarding the tool he must reaccustom himself to the handle or grip of the new lathing hammer.

With these and other desiderata in view, it will be appreciated that it is considered an object of this invention to provide an improved lathing hammer which comprises a body on which a hammering head and a blade are detachably mounted, so that as the blade and hammering head become worn, these parts alone can be replaced and the old grip or han-

dle, to which the lather has become accustomed, can be used with the new or replacement parts.

Another object of the invention is to provide a lathing hammer having a body to which a hammering head is detachably fastened, which hammering head has portions removed therefrom decreasing its weight, thus enabling the entire tool to be accurately and perfectly balanced. Should the application of one head to the body of the tool cause it to be out of the desired balance, another head which has greater or less portions removed can be substituted therefor, thus enabling the entire tool to be perfectly balanced in accordance with the desire of the lather.

Another object of the invention is to provide a lathing hammer or axe comprising a body having a detachable blade and a detachable hammering head mounted thereon, with a connection extending longitudinally through the body connecting the blade and the hammering head so that the hammering head on being tightened into place on the body will cause the blade to be likewise tightened in place on the body.

Still a further object of the invention is to provide a lathing hammer comprising a body having a bolt extending longitudinally therethrough on which the hammering head is adapted to be screwed and which is so constructed that the bolt may be rotatably adjusted so that when the hammering head is tightened up against the body, it will assume a proper position with respect to the body on being tightened in place.

Another object of the invention is to provide a lathing hammer having a detachable hammer head and a detachable blade, which parts are so constructed that no tools will be required to assemble and disassemble the parts of the hammer.

With the foregoing and other objects in view, which will be made manifest in the following detailed description, and specifically pointed out in the appended claims, reference is had to the accompanying drawing for an illustrative embodiment of the invention, wherein:

Fig. 1 is a view in side elevation of the improved lathing hammer.

Fig. 2 is a view in end elevation, taken in the direction of the arrow 2 upon Fig. 1.

Fig. 3 is a view in end elevation of the hammer, taken in the direction of the arrow 3 upon Fig. 1.

Fig. 4 is a longitudinal vertical section taken substantially upon the line 4—4 upon Fig. 2, in the direction indicated.

Fig. 5 is a horizontal section taken upon the line 5—5 upon Fig. 4, in the direction indicated.

Fig. 6 is a vertical section taken upon the line 6—6 upon Fig. 4.

Fig. 7 is a perspective view of the blade, forming a part of the improved lathing hammer.

Fig. 8 is a perspective view of the bolt, forming a part of the improved lathing hammer.

Fig. 9 is a partial view in perspective, illustrating the upper end of the body of the improved hammer.

Referring to the accompanying drawing, wherein similar reference characters designate similar parts throughout, the improved lathing hammer comprises a body generally designated at 10, having a shank 11 on which the grip or handle 12 is provided. The exact nature of the handle 12 is immaterial in so far as the present invention is concerned, it being understood that any conventional or desirable form of handle may be employed.

There is illustrated, however, a wooden grip which is slipped onto the end of the shank and held in place as by rivets 13. If desired, however, a leather grip formed of leather washers held in place on the shank 11 may be used.

On the upper end of the body there is formed a body head 14, shown as being tapered in form, the large end being adapted to have a hammering head secured thereto against. The small end of the body head 14 has a vertical groove or slot 15 formed therein, which is crossed by a wide lateral groove or recess, indicated at 16. A bore 17, which may be a hole drilled through the steel head of the body, extends longitudinally through the head 14 opposite the recess or notch 16.

This bore is adapted to receive a bolt 18, having one end threaded as at 19, and having a portion 20 near its opposite end formed with reduced diameter, thus defining a cylindrical head 21 on the bolt.

A blade is provided of suitable steel, which is indicated at 22. This blade is preferably of uniform thickness except adjacent its outer end where it may be beveled or sharpened to a fine cutting edge 23. Near the inner end of the blade there is formed an aperture 24 and the portion of the blade between the aperture and the extreme inner end of the blade is bowed or bent laterally as indicated at 25. This portion is equal in length

to the length of the reduced portion 20 on the bolt 18, and the difference between the diameters of the reduced portion 20 and of the remainder of the bolt is such that the portion 25 will be accommodated about the reduced portion 20. Two holes, indicated at 26, are drilled through the head 21 of the bolt, these being arranged approximately 90° apart, and are to be used for a purpose hereinafter to be described.

On the opposite end of the body from the blade there is adapted to be positioned a hammering head 27 which has a drilled and tapped hole 28 formed therein, thus providing threads complementary to the threads 19 on the bolt 18. The hammering head 27 is shown as provided with a square flat roughened or knurled hammering face, although it will be readily appreciated that the shape of the face is immaterial and that the face instead of being flat may be convex, and also instead of having the roughened or knurled surface that the face may be smooth. The preferred form of construction, however, is substantially as that shown upon the drawing. The inner end of the hammering head is adapted to be tightened up against the large end of the body head 14 by screwing it upon the bolt 18.

A small hole 29 is drilled into the large end of the body. This hole receives a spring 31, which is compressed behind a plunger or locking pin 32. The locking pin 32 has a central portion of reduced size or reduced diameter, forming shoulders serving as stops engageable upon a pin or wedge 33 which pins the locking pin within the hole 29 but enables it to be moved therein between limits. When the plunger or locking pin is in projected position, as shown in Fig. 4, it enters a recess 34 in the hammering head 27, which recess has its under side open so that the end of the locking pin 32 may be engaged, as by the finger nail, and moved into retracted position in the hole 29 against the action of coil spring 31. When the locking pin is in the projected position it locks the hammering head against rotation and prevents its unscrewing from bolt 18.

As clearly shown upon Figs. 1, 4 and 5, the hammering head 27 may have recesses 35 bored or otherwise formed therein. These recesses may be of various depths and in some instances they may be continued through the entire hammering head. In this manner the weights of different hammering heads may be varied and, by selecting a hammering head of the proper weight, the improved lathing hammer can be caused to have the proper balance in accordance with the desire of the lather.

The improved lathing hammer may be disassembled as follows. The locking pin 32 is pressed inwardly to move the locking pin out of engagement with the hammering head

27. The hammering head can then be unscrewed from the end of bolt 18, after which the bolt 18 may be caused to slide toward the right, as shown in Fig. 4, allowing the blade 5 to be moved out of the vertical groove or slot 15. As soon as the blade has been removed from the slot or groove 15, the blade may be moved laterally out of engagement with the head of the bolt. Assembly of the improved 10 tool can be accomplished in the converse manner, by first positioning the blade 22 against the end of the bolt so that the head 21 partially projects into aperture 24, and portion 25 of the blade is accommodated 15 around the reduced portion 20. After this is accomplished, the blade and bolt are caused to slide toward the left, as shown in Fig. 4, causing the inner end of the blade to enter the groove or slot 15. In this position the 20 head 27 is ready to be applied. However, the threads on the interior of the hammering head 27 cannot be accurately placed so that when the head is tightened up against the body it will assume the proper position with 25 respect thereto. In order to provide for this, it will be noted that the bolt 18 is cylindrical and has a cylindrical head enabling it to be rotatably adjusted. The bolt is then rotatably 30 adjusted and held in adjusted position by any suitable implement, such as for example a lathing nail, one of which is illustrated in applied position at 36 in Fig. 5. This lathing nail is inserted through either of the apertures 26 and can be caused to rotatably 35 adjust the bolt 18 into the desired position and hold it in this position while the hammering head 27 is being screwed up tight against the end of the body head 14. Only a small amount of experimentation is necessary 40 to properly adjust the bolt 18 so that when the hammering head is screwed up it will assume the proper position with respect to the body, as shown upon the drawing. During the screwing up of the hammering head 45 it will readily be appreciated that the locking pin 32 must be held retracted against the action of the spring 31 but after the head has been tightened into position the locking pin can be released, locking the head against 50 unscrewing. When the tool has been thus assembled, the lathing nail 36 can be withdrawn from the aperture 26 and discarded. All of the parts will be firmly held in position 55 and the tool is ready for use. It will readily be appreciated by the improved construction that no tools, such as a wrench, or a screw driver, or the like, need be employed in assembling or disassembling the improved tool. The only implement which is necessary 60 for these purposes is a lathing nail, plenty of which are usually available.

The advantages of the improved lathing hammer are briefly as follows. When the cutting edge 23 becomes dull, the lather can 65 easily and quickly substitute a new blade hav-

ing a sharp edge for the blade of the tool, thus postponing sharpening of the blade until a more suitable time than when he is busily engaged applying laths. If the sharpening and resharpening of the blade 70 reduces its length to any material extent, tending to throw the tool out of balance, the hammering head 27 may be removed and another head substituted, restoring the balance. If the length of the blade is so far reduced as 75 to reduce the usefulness of the lathing hammer, a new blade may be supplied at a small cost. In making all of these changes it will be appreciated that the handle or grip is in no way affected so that if the lather has become accustomed to the tool he will not be forced to reaccustom himself to the grip of a new lathing hammer. Under all circumstances the lathing hammer may be given the 80 desired balance by selecting the proper hammering head having the requisite weight. In the course of time it frequently occurs that the rough or coarse knurling on the face of the hammering head wears and becomes 85 smooth. If the lather desires this rough surface, he can easily and quickly replace it by the application of a new hammering head. Heretofore where tools of this type have 90 been made with the hammering face and the blade out of one and the same piece of metal, some difficulty has been experienced in obtaining the proper temper. The improved construction enables these parts of the tool to have the proper temper and furthermore 95 as the blade is of uniform thickness an even temper can be given throughout substantially its entire length so that in the course of resharpening the blade metal is not encountered of weaker or poorer temper, as in the 100 case of integral hatchet heads which usually have tapered blades.

Various changes may be made in the details of construction without departing from the spirit or scope of the invention as defined by the appended claims. It will be understood in the following claims that the term "lathing hammer" is not to be restricted to tools for applying laths only but that in so using the term the invention may be equally applied to similar tools used for other purposes.

I claim:

1. A lathing hammer comprising a body, a blade arranged on one side of the body, a bolt extending longitudinally through the body, said bolt having a head adapted to engage the blade and fasten the blade to the body, and a hammering head adapted to be screwed onto the opposite end of the bolt to cause the bolt to tighten the blade in place, said bolt being rotatably adjustable enabling the hammering head to be tightened into proper position with respect to the body.

2. A lathing hammer comprising a body, a blade arranged on one side of the body, a bolt

extending longitudinally through the body, said bolt having a head adapted to engage the blade and fasten the blade to the body, a hammering head adapted to be screwed onto the opposite end of the bolt to cause the bolt to tighten the blade in place, said bolt being rotatably adjustable enabling the hammering head to be tightened into proper position with respect to the body, and spring urged locking means on the body engageable with the body engaging face of the hammering head to lock the hammering head against unscrewing.

3. A lathing hammer comprising in combination a body having a groove on one side thereof, a blade receivable in the groove, said blade having an aperture extending transversely therethrough, and means adapted to be positioned in said aperture from one side of the blade for tightening the blade against the body.

4. A lathing hammer comprising in combination a body having a groove on one side thereof, a blade receivable in the groove, said blade having an aperture extending transversely therethrough, and means extending longitudinally through the body adapted to be positioned in the aperture from one side of the blade and adapted to be caused to tighten the blade against the body.

5. A lathing hammer comprising in combination a body having a groove on one side thereof, a blade receivable in the groove, said blade having an aperture extending transversely therethrough, a bolt extending longitudinally through the body having a head partially extending through the aperture from one side of the blade, the bolt adjacent the head being of reduced size to accommodate a portion of the blade, and means for causing the bolt to tighten the blade in the groove.

6. A lathing hammer comprising in combination a body having a groove on one side thereof, a blade receivable in the groove, said blade having an aperture therein, a bolt extending longitudinally through the body having a head partially extending through the aperture, the bolt adjacent the head being of reduced size to accommodate a portion of the blade, and means for causing the bolt to tighten the blade in the groove comprising a hammering head adapted to be screwed onto the bolt against the opposite side of the body.

7. A lathing hammer comprising in combination a body having a groove on one side thereof, a blade receivable in the groove, said blade having an aperture therein, a bolt extending longitudinally through the body having a head partially extending through the aperture, the bolt adjacent the head being of reduced size to accommodate a portion of the blade, means for causing the bolt to tighten the blade in the groove comprising a hammer-

ing head adapted to be screwed onto the bolt against the opposite side of the body, said bolt being rotatably adjustable, and means on the bolt enabling it to be held in adjusted position whereby the hammering head may be tightened against the body in proper position with respect thereto.

8. A lathing hammer comprising in combination a body having a groove on one side thereof, a blade receivable in the groove, said blade having an aperture therein, a bolt extending longitudinally through the body having a head partially extending through the aperture, the bolt adjacent the head being of reduced size to accommodate a portion of the blade, means for causing the bolt to tighten the blade in the groove comprising a hammering head adapted to be screwed onto the bolt against the opposite side of the body, said bolt being rotatably adjustable, means on the bolt enabling it to be held in adjusted position whereby the hammering head may be tightened against the body in proper position with respect thereto, and means for locking the hammering head in tightened position against unscrewing, comprising a spring urged plunger in the body movable in a direction parallel to the bolt into engagement with the hammering head.

9. A lathing hammer comprising in combination a body, a hammering head, means providing a threaded connection between the body and the hammering head whereby the hammering head may be attached and detached, said means being rotatably adjustable so that the hammering head may be caused to assume a proper position on being tightened against said body, and a latch mounted upon the body engageable with the hammering head for locking the hammering head against unscrewing and thus holding the rotatable means against rotation.

10. A lathing hammer comprising in combination a body, a blade, said body and blade having engaging surfaces which prevent the blade from turning with respect to the body, a hammering head detachable from the body, and means connecting the blade and hammering head to the body, said means being rotatably adjustable relatively to the blade so as to enable proper positioning of the hammering head on the body.

11. A lathing hammer comprising in combination a body, a blade, said body and blade having engaging surfaces which prevent the blade from turning with respect to the body, a hammering head detachable from the body, means connecting the blade and hammering head to the body, said means being rotatably adjustable relatively to the blade so as to enable proper positioning of the hammering head on the body, and means for locking the hammering head against turning relatively to the body.

12. A lathing hammer comprising in com-

bination a body, a blade, said body and blade having engaging surfaces which prevent the blade from turning with respect to the body, a hammering head detachable from the body, 5 and a bolt connecting the blade and hammering head through the body, one end of the bolt being threadedly connected to the hammering head and the other end of the bolt having a head engaging the blade.

10 13. A lathing hammer comprising in combination a body, a blade, said body and blade having engaging surfaces which prevent the blade from turning with respect to the body, a hammering head detachable from the body, 15 and a bolt connecting the blade and hammering head through the body, one end of the bolt being threadedly connected to the hammering head and the other end of the bolt having a head rotatably adjustable with respect to the blade so that although the blade 20 may not turn relatively to the body the bolt may be turned enabling the head to assume a proper position with respect to the body.

14. A lathing hammer comprising in combination a body, a blade, said body and blade having engaging surfaces which prevent the blade from turning with respect to the body, a hammering head detachable from the body, 25 and a bolt connecting the blade and hammering head through the body, one end of the bolt being threadedly connected to the hammering head and the other end of the bolt having a head engaging and rotatable relatively to the blade.

30 15. A lathing hammer comprising in combination a body, a blade, said body and blade having engaging surfaces which prevent the blade from turning with respect to the body, a hammering head detachable from the body, 35 and a bolt connecting the blade and hammering head through the body, one end of the bolt being threadedly connected to the hammering head and the other end of the bolt having a head engaging and rotatable relatively to 40 the blade, and means locking the head against turning relatively to the body.

45 16. A lathing hammer comprising in combination a body having a groove on one side thereof, a blade receivable in the groove, said 50 blade having an aperture extending transversely therethrough, and means adapted to be positioned in said aperture from one side of the blade for tightening the blade against the body, said blade presenting a concavity 55 adjacent the aperture to partially receive said means.

In testimony whereof I have signed my name to this specification.

JOSEPH W. HENNECKE.
